United States Patent Office

Des. 229,339
Patented Nov. 20, 1973

229,339

CIGARETTE LIGHTER

Kenjiro Goto, Tokyo, Japan, assignor to Mansei Kogyo
Kabushiki Kaishya, Saitama, Japan

Filed Mar. 13, 1972, Ser. No. 234,461

Term of patent 14 years

Int. Cl. D27—05
U.S. Cl. D48—27 R

FIG. 1 is a top plan view of a cigarette lighter showing my new design;

FIG. 2 is a front end elevational view thereof;

FIG. 3 is a side elevational view thereof;

FIG. 4 is a rear end elevational view thereof;

FIG. 5 is a bottom plan view thereof; and

FIG. 6 is a front perspective view thereof.

I claim:

The ornamental design for a cigarette lighter, substantially as shown.
